UNITED STATES PATENT OFFICE.

SIGISMUND M. MICHELSON, OF MILWAUKEE, WISCONSIN.

TRUNK-TRAY.

SPECIFICATION forming part of Letters Patent No. 278,580, dated May 29, 1883.

Application filed March 27, 1883. (No model.)

To all whom it may concern:

Be it known that I, SIGISMUND M. MICHELSON, of Milwaukee, in the county of Milwaukee, and in the State of Wisconsin, have invented certain new and useful Improvements 5 in Trunk-Trays; and I do hereby declare that the following is a full, clear, and exact description thereof.

My invention relates to trunks; and it consists 10 in certain novel means for sustaining one or more of the trunk-trays during the operations of packing and unpacking, or whenever it is desirable to get at the contents of that portion of the trunk below the upper tray, all as 15 will be more fully set forth hereinafter.

In the drawings, Figure 1 is a perspective view of an open trunk, showing the upper tray sustained by my invention upon the front edge of the trunk-top; and Fig. 2 is a similar view, 20 showing two of the trays thus sustained. Fig. 3 is a detail view, showing the construction and operation of the supporting device.

A is a trunk of any ordinary construction, provided with a top, A', hinged thereto, and 25 with trays B B. The trunk-top has a flat front, a', level with the front of the trunk proper when closed, and a metal strip or valance, A², surrounds the front and side edges of the top, so as to make a tight joint with 30 the trunk when the top is closed.

C is a catch or supporting device, of which one or more is to be applied to the bottom of each tray; and it consists of a flat strap of metal bent back upon itself a short distance 35 at one end, and provided with holes at the other end, (or the whole device may be cast

solid, if desired,) and bolts or screws are passed through said holes into or through the bottom of the tray, thus securing the catch thereto.

When the tray has been lifted out of the 40 trunk it is placed on the flat front a' of the trunk-top, and the projecting valance A² thereof is forced between the doubled end of the catch G, as shown in Fig. 3, thereby holding the tray firmly in place and guarding against 45 its being accidentally knocked off by a touch or jar, or by moving the contents back and forth in the tray, as might happen if it were not so secured. In Fig. 2 I have shown two 50 trays thus supported, and the number that may be thus supported is only limited by the length of the trunk and the width of the trays from end to end.

Having thus described my invention, what I claim as new, and desire to secure by Letters 55 Patent, is—

In combination with a trunk-tray, a catch secured on the under side thereof, and adapted, when the tray is removed from the body of the trunk, to receive the valance of the 60 trunk-top, so that the tray will be supported on the front edge of the top when the latter is open, substantially as set forth.

In testimony that I claim the foregoing I have hereunto set my hand, on this 20th day 65 of March, 1883, in the presence of two witnesses.

SIGISMUND M. MICHELSON.
